DESIGN.

O. BRINTZENHOFE.

VACUUM CLEANER.

APPLICATION FILED AUG. 10, 1920.

57,109.

Patented Feb. 22, 1921.

Inventor:
Otto Brintzenhofe,
by Albert G. Davis,
His Attorney.

UNITED STATES PATENT OFFICE.

OTTO BRINTZENHOFE, OF CLEVELAND, OHIO, ASSIGNOR TO ELECTRIC VACUUM CLEANER COMPANY, INC., A CORPORATION OF NEW YORK.

DESIGN FOR A VACUUM-CLEANER.

57,109.

Specification for Design.

Patented Feb. 22, 1921.

Application filed August 10, 1920. Serial No. 402,704. Term of patent 14 years.

To all whom it may concern:

Be it known that I, OTTO BRINTZENHOFE, a citizen of the United States, residing at Cleveland, in the county of Cuyahoga, State of Ohio, have invented a new, original, and ornamental Design for a Vacuum-Cleaner, of which the following is a specification.

The accompanying drawing is a perspec-

tive view of a vacuum cleaner showing my new and original design.

What I claim is—

The ornamental design for a vacuum cleaner as shown.

In witness whereof, I have hereunto set my hand this 6th day of August 1920.

OTTO BRINTZENHOFE.
